MILES F. MOORE
INVENTOR.
BY Victor J. Evans
ATTORNEYS.

UNITED STATES PATENT OFFICE.

MILES F. MOORE, OF SAN FRANCISCO, CALIFORNIA, ASSIGNOR OF ONE-HALF TO
WILLIAM F. HILLS, OF MOUNTAIN VIEW, CALIFORNIA.

SPRING-OILING DEVICE.

Application filed July 21, 1923. Serial No. 653,036.

To all whom it may concern:

Be it known that I, MILES F. MOORE, a citizen of the United States, residing at San Francisco, in the county of San Francisco and State of California, have invented new and useful Improvements in Spring-Oiling Devices, of which the following is a specification.

This invention relates to improvements in 10 spring oiling devices, and has particular reference to means for lubricating the leaves of an automobile spring. It is obvious, however, that the same might be used in similar springs other than those employed upon 15 motor vehicles.

The principal object of this invention is to produce a simple container for a lubricant, and to further provide means for feeding this lubricant to the leaves of a spring so 20 that the same will gradually work between the leaves, thus preventing excessive friction thereby prolonging the life of the spring.

A further object is to produce a device 25 which is simple in construction, neat in appearance and one which may be readily applied to the average automobile, without altering the construction of the same.

Other objects and advantages will be apparent during the course of the following 30 description.

In the accompanying drawings forming a part of this specification, and in which like numerals are employed to designate like parts throughout the same,

Figure 1 is a perspective view of my device,

Figure 2 is a side elevation of a spring having my device applied thereto,

Figure 3 is a vertical cross section of the 40 preferred form of my device shown in Figure 1,

Figure 4 is a fragmentary detail view of the filling well,

Figure 5 is a plan view of the blank out 45 of which my device is formed, and

Figure 6 is a vertical cross section of the modified form of my device.

Applicant is aware of the fact that devices 50 have been applied to springs for the purpose of forcing a lubricant between the leaves thereof, such as wedges having a passageway therein for the grease. These devices, however, are cumbersome, hard to manipulate and do not feed a steady amount,

but only small quantities of lubricant, whereas large quantities of lubricant are essential in order to secure the proper lubrication.

In the accompanying drawings wherein for the purpose of illustration is shown a preferred embodiment of my invention, the 60 numeral 5 designates the ordinary leaf spring, while the numeral 6 designates the body of my device as whole.

By referring to Figure 1, it will be noted 65 that my device comprises a bottom portion 7, and upwardly extending portions 8 and 9. This bottom portion forms a reservoir 11 within which the lubricant is placed.

A filling well is shown at 12 has a cap 13 70 normally held closed by a spring 14 (see Fig. 4). The upwardly extending portions 8 and 9 are channel-shaped and each section contains a wick as shown at 16 and 17, respectively. These wicks have their lower ends extending downwardly and into the reservoir 11 and have their upper surface in contact with the sides of the leaves of the spring as best shown in Figure 3.

A cover 18 closes the reservoir 11, and also 75 contacts the under-side of the spring 5. It will be observed that the cover has formed integral therewith side members 18' which are curved at their extremities. The sides of the cover assist in positioning the wicks in the portions 8 and 9 and each curved extremity retains the end of each wick at a substantially right angle to the body of the wick, thereby affording a more positive capillary attraction than could be had if all of the body of the wick were in the same plane. A top plate 19 has a downwardly extending spring 21 secured to its under surface. This top plate is attached to the upwardly extending portions 8 and 9 as by 80 cotter pins 22 and 23.

By referring to Figure 6, it will be noted 85 that the construction is substantially the same as that shown in Figure 3, with the exception that the reservoir is placed above the spring as shown at 24 and that the wicks extend from this reservoir downwardly along the sides of the spring. In this form I provide a filling opening 26 which is closed by 90 a suitable cap. The retaining means for this form of lubricator consists of a bottom plate 27, similar to the plate 19, to which a spring 28 is secured, which spring contacts the under-side of the leaf spring to be lubricated.

The plate 27 is secured to the device by cotter-pins in a manner similar to that described in the preferred form.

It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention, I claim:

The combination with a leaf spring, of

a device for lubricating the surfaces between the leaves, comprising a lubricant holding receptacle, wick-holding channel portions formed integral with the receptacle, a cover for the receptacle including side members terminating in curved extremities for positioning the ends of the wicks in the receptacle, a top plate secured to the extremities of the channel portions, and a spring secured to said top plate for engaging the leaf spring.

In testimony whereof I affix my signature.

MILES F. MOORE.
